CLAIM

The ornamental design for a baby bottle, as shown and described.

DESCRIPTION

FIG. 1 is a front elevation view of a baby bottle, wherein the front and the back of views of the bottle are identical;

FIG. 2 is side elevation view of the bottle of FIG. 1, wherein both sides of the bottle are identical;

FIG. 3 is an enlarged top plan view of the bottle of FIG. 1; and,

FIG. 4 is an enlarged bottom plan view of the bottle of FIG. 1. The broken lines in the drawings represent environmental subject matter and form no part of the claimed design.
